Primary Examiner—Paula A. Mortimer[57] **CLAIM**

The ornamental design for a new image tie with mirror case, as shown.

DESCRIPTION

FIG. 1 is a front elevational view of a new image tie with mirror case showing my new design;

FIG. 2 is a rear elevational view of FIG. 1;

FIG. 3 is a left side elevational view of FIG. 1;

FIG. 4 is a right side elevational view of FIG. 1;

FIG. 5 is a top plan view of the new image tie with mirror case of FIG. 1; and,

FIG. 6 is a bottom plan view of the new image tie with mirror case of FIG. 1.

The necktie in FIGS. 2, 3, and 4 is drawn broken away to show indeterminate length.
